UNITED STATES PATENT OFFICE.

ARTHUR K. CAMP, OF MILWAUKEE, WISCONSIN.

DESIGN FOR A SPOON.

SPECIFICATION forming part of Design No. 20,989, dated August 11, 1891.

Application filed July 11, 1891. Serial No. 399,214. Term of patent 7 years.

To all whom it may concern:

Be it known that I, ARTHUR K. CAMP, a citizen of the United States, residing at Milwaukee, in the county of Milwaukee and State 5 of Wisconsin, have invented and produced a new and original Design for Spoons or Similar Articles of Table-Ware; and I do declare the following to be a full, clear, and exact description of the same, reference being had to 10 the accompanying drawing, forming a part thereof.

My design is intended to be materialized in or upon a spoon or similar article of table-ware, the handle of which is ornamented with 15 the representation of a hop-vine in relief so arranged as to simulate a miniature vine wound spirally around the narrower portion of the handle, and thence carried around the entire edge of the wide end of said handle. 20 Between the apparent windings of the vine on the face or upper side of the handle are spaces for inscriptions, (such as the words "Milwaukee Souvenir," shown,) while the central portion of the face of the broad end of 25 the handle is ornamented with the representation of an ancient beer mug or tankard having a handle and a top, which latter is shown as being partially open. The bowl or lower part of the spoon or other article is ornamented

with the representation of a brewery, and at 30 the point of juncture of this part and the handle there is shown a hop-leaf, while near this point the heretofore-described hop-vine shows on each side of the narrow portion of the handle. 35

Having thus described my design, what I claim therein is—

The design for a spoon or similar article of table-ware, as herein shown and described, comprising the representation of a hop-vine 40 wound around the narrower portion of the handle and thence continuing entirely around the edge of the wider end of said handle, said vine showing on both sides of the narrow portion of the handle, adjacent to the lower part 45 thereof, the representation of an ancient beer mug or tankard in the center of the face of said wide end of the handle, said mug or tankard having a handle and a top, the latter being shown partially open, and the representation of a brewery upon the lower part of the said article. 50

In testimony whereof I affix my signature in presence of two witnesses.

ARTHUR K. CAMP.
